ASH TRAY AND RECEPTACLE

Harold Leiman, Astoria, Long Island, N. Y.

Application March 28, 1940, Serial No. 326,328

2 Claims. (Cl. 131—235)

This invention relates to new and useful improvements in an ash tray and receptacle.

The invention has for an object the construction of an article as mentioned which is characterized by a receptacle provided with a cover having a frusto-conical top wall extending therein and formed with a bottom opening, and a novel arrangement of a spherical member resting on the edges of the opening for closing the same and operating in a manner as will become clear as this specification proceeds.

Still further the invention contemplates providing the spherical member with several recesses on its surface into which the lighted end of a cigarette may be engaged and snuffed out.

Still further the invention contemplates providing the spherical member with a handle by which it may be manipulated.

Still further the invention contemplates the association of a novel cigarette or cigar holder with the ash tray and receptacle.

Another object of the invention resides in the provision of a novel stand for supporting the receptacle.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure—

Fig. 1 is a perspective view of an ash tray and receptacle constructed in accordance with this invention.

Fig. 2 is a transverse vertical central sectional view of Fig. 1.

Fig. 3 is a plan view of Fig. 1 but illustrated with the spherical member removed.

Fig. 4 is a perspective view of the spherical member and handle per se.

Fig. 5 is a central vertical sectional view of Fig. 4.

Fig. 6 is a fragmentary vertical sectional view taken on the line 6—6 of Fig. 2.

Fig. 7 is a vertical sectional view of an ash tray and receptacle constructed in accordance with another embodiment of this invention.

Fig. 8 is a fragmentary vertical sectional view of the spherical member shown in Fig. 7.

Fig. 9 is a horizontal sectional view taken on the line 9—9 of Fig. 7.

Fig. 10 is a vertical sectional view taken on the line 10—10 of Fig. 9 with the closure member omitted from this figure.

Figs. 11 and 12 are vertical sectional views, showing still further modified forms of the invention.

The ash tray and receptacle, in accordance with this invention, includes a jar or receptacle 10 preferably of glass or other attractive material. A cover 11 is mounted on the top of the receptacle. This cover has an annular threaded portion 11^a which threadedly engages complementary threads formed on the top of the receptacle 10. The cover 11 is also provided with a frusto-conical top wall section 11^b extending into the receptacle. This section 11^b has a bottom opening 11^{bb}. The top edges of the sections 11^a and 11^b are secured together by bending one of the edge portions of one of the sections over the edge portion of the other section to grip and connect the parts.

A spherical member 12 rests on the edge of the opening 11^{bb} and forms a closure of this opening. This spherical member 12 has several recesses 13 formed in its surface into which the lighted end of a cigarette may be engaged and snuffed out. A handle 14 is connected with the spherical member and extends upwards by which the spherical member may be moved.

The handle 14 comprises a stem portion 14^a mounted on and radially projecting from the spherical member 12. This stem has a knob 14^b at its outer end. The spherical member 12 may comprise china material, composition material, metal or other suitable materials.

A small groove 16 formed in the top portion of the material of the wall 11^b so that when the handle 14 is inclined laterally and rested within the groove 16, it serves to hold the spherical member 12 in a position in which one of the recesses 13 is directed upwards. This facilitates engaging the lighted end of a cigarette into the top recess 13 to snuff it out. The groove 16 serves to hold the spherical member 12 in a stationary position during the snuffing operation.

A cigarette holder is associated with the ash tray and receptacle. This cigarette holder essentially comprises a strand of wire 18 having a central wavy chord area 18^a and arcuately shaped end portions 18^b. These end portions 18^b repose within an annular groove 20 formed along the inside top edge portions of the wall 11^b. A cigarette 21 may be engaged in between one of the convolutions of the section 18^a of the wire 18 and the wall of the cover 11. The resiliency of the ends 18^b engaging the groove 20 is depended upon to hold the cigarette holder in posi-

tion. It may be removed by forcing it out of its places. The stubs of cigarettes after being extinguished may be dropped through the opening 11^{bb} into the receptacle 10.

In Figs. 7 to 10 inclusive another form of the invention has been disclosed which distinguishes from the prior form in several respects. In this form of the invention there is a spherical member 12' formed of glass or other material which is not readily adapted to have threads formed therein. A handle 14' is associated with this spherical member. Specifically, a screw 23 engages through the spherical member 12' and threadedly engages into a socket portion formed in the end of the handle 14'. Moreover, the receptacle 10 is provided with a cover 11' having a top outwardly extending flange engageable across the top of a supporting stand for the receptacle. This stand comprises a metallic receptacle 25 into which the glass receptacle or jar 10 may engage. The receptacle 25 has a rolled top edge 25a. The flange portion of the cover 11' extends over this rolled edge.

The receptacle 25 is attached upon the top of a pedestal 26 by a bolt 27 which engages through the bottom of the receptacle 25 and which passes through the pedestal 26 and which is connected with a heavy weight 28 reposed within the hollow base of the pedestal 26. The pedestal 26 has several felt pieces 29 or other soft pieces attached to its bottom, so that it may rest upon objects without damaging them.

The ash tray and receptacle is provided with a modified form of cigarette holder which comprises a stand of wire 18' having a pair of raised central wavy chord sections 18^{aa} between which there are arcuate sections 18^{bb}. These arcuate sections engage within a groove 20 formed in the cover 11' for maintaining the cigarette holder in position. Cigarettes may be supported on either or both sides of the holder 18'. The dot and dash lines 21 in Fig. 9 indicates two cigarettes thus supported.

In other respects this form of the invention is similar to the previous form.

In Fig. 11, the receptacle 30 is in the form of a sphere made of an upper section 31 and a lower section 32, slidably joined together at 33. In this form of the invention the jar 10' rests in the bottom portion of the lower section 32 and the mouth 10^a of the jar 10' is in contact with the lower outer portion of the frusto-conical top wall section 11^b. In other respects this form of the invention is similar to that shown in Figs. 7-10 and the various parts may be recognized by the similar corresponding numerals.

In Fig. 12 the receptacle 34 is formed of a cylindrical upper cover section 35 and lower section 36 slidably joined together at 37. In this form of the invention the frusto-conical wall section 38 is made integral with the cover section 35.

It is to be understood that the size and material used in this device and the shape of the spherical member may be changed as desired. The spherical members may also be made without the recesses 13, in large size devices, where the spherical members are located too deep within the device.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. In an ash tray and receptacle, a cover for said receptacle having a frusto-conical downwardly projecting wall portion with its sides converging to form an acute angle, said cover being formed with a coaxial opening at the bottom of its converging sides, a spherical member resting on the edge of said opening closing the same, and said spherical member having a diameter slightly greater than said opening and of a size so that its top sets at a substantial distance below the top edge portion of said converging sides forming a large unobstructed compass above said spherical member wherein ashes may collect, and means extending from said spherical member for facilitating the lifting thereof out of its normal position so that the collected ashes may pass through said opening into said receptacle, comprising a thin handle having one end attached to said spherical member and a free end projected axially from said spherical member beyond the top edge portion of said converging sides to be manually grasped for lifting said spherical member, and semi-spherical recesses formed in said spherical member and into which the lighted end of a cigarette may be engaged for snuffing the same.

2. In an ash tray and receptacle, a cover for said receptacle having a frusto-conical downwardly projecting wall portion with its sides converging to form an acute angle, said cover being formed with a coaxial opening at the bottom of its converging sides, a spherical member resting on the edge of said opening closing the same, and said spherical member having a diameter slightly greater than said opening and of a size so that its top sets at a substantial distance below the top edge portion of said converging sides forming a large unobstructed compass above said spherical member wherein ashes may collect, and means extending from said spherical member for facilitating the lifting thereof out of its normal position so that the collected ashes may pass through said opening into said receptacle, comprising a thin handle having one end attached to said spherical member and a free end projected axially from said spherical member beyond the top edge portion of said converging sides to be manually grasped for lifting said spherical member, and semi-spherical recesses formed in said spherical member and into which the lighted end of a cigarette may be engaged for snuffing the same, and a groove formed at the top of said converging sides and into which an intermediate portion of said handle is adapted to be engaged for holding said spherical member stationary while a cigarette is being snuffed.

HAROLD LEIMAN.
